UNITED STATES PATENT OFFICE.

GUY B. COLLIER, OF KINDERHOOK, NEW YORK.

AEROPLANE-PROPELLER.

1,393,753.

Specification of Letters Patent. Patented Oct. 18, 1921.

Application filed July 15, 1918. Serial No. 244,841.

To all whom it may concern:

Be it known that I, GUY B. COLLIER, a citizen of the United States, residing at Kinderhook, in the county of Columbia and State of New York, have invented certain new and useful Improvements in Aeroplane-Propellers; and I do hereby declare the following to be a full, clear, and exact description of the invention, such as will enable others skilled in the art to which it appertains to make and use the same.

The present invention relates to propellers and more particularly to apparatus of this character designed for the propulsion of aeroplanes.

The existing types of aeroplane propellers now in use are efficient throughout only a comparatively small portion of the blade length and owing to their design and the shape of the blades cause a severe swirling of the air which seriously detracts from the efficiency of the blade. Furthermore these propellers, owing to the absence of any construction for changing the pitch, must necessarily be designed for a single speed of revolution and decrease markedly in efficiency at speeds above and below this theoretical best speed.

One object of the present invention is to improve the construction of propellers more particularly adapted for embodiment in aeroplanes in such a manner that the area of the blades is utilized to the utmost, while at the same time minimizing the eddy currents and other factors which tend to reduce the efficiency of the blade.

A further object of the invention is to provide for a variation in pitch of the propeller blade between desired limits so that the blades may at all times be pitched at the angle best suited for any given speed of revolution, and in addition enable the speed of the aeroplane to be varied throughout a greater range.

With these objects in view the several features of the invention consist in certain novel features of construction, combinations and arrangements of parts hereinafter described and claimed, the advantages of which will be obvious to those skilled in the art from the following description.

In the accompanying drawings illustrating the preferred form of the invention, Figure 1 is a rear elevation illustrating clearly the improved propeller construction; Fig. 2 is a section in elevation of the pro-

peller shown in Fig. 1 and illustrating in addition the mechanism for controlling the pitch of the blades; Fig. 3 is a partially diagrammatic view illustrating the operating mechanism for each blade; Fig. 4 is a detail illustrating an elevation of the operating mechanism taken upon the line 4-4 of Fig. 2; Fig. 5 is a detail of the mechanism for partially rotating the spider; Fig. 6 is a section in elevation of the same propeller illustrating a modified form of mechanism for varying the pitch of the blades; Fig. 7 is a detail illustrating the operating connections for swinging each blade; Fig. 8 is a detail taken upon the line 8-8 of Fig. 6; Fig. 9 is a detail taken upon the line 9-9 of Fig. 6; Fig. 10 is a detail illustrating the rack and pinion mechanism for changing the pitch of the blades; and Fig. 11 is a rear elevation of the propeller with the modified form of blade controlling mechanism embodied therein.

The propeller shown in the illustrated embodiment of the invention comprises generally inner and outer annular shells designed to present a minimum resistance to the passage of the propeller through the air and to eliminate eddy losses existing in ordinary propellers due to radial flowing of air and a series of blades interposed between the shells and having their leading edges extending radially. The blades are swung about the leading edges to vary the pitch through mechanism connected to each blade adjacent the discharge edge and designed to move all of the blades synchronously so that the pitch of the several blades shall be the same in all positions. This pitch angle of the blades may be varied between 30 and 60 degrees and the outer and inner edges of each blade are designed in such a manner that at the minimum pitch angle the outer edge contacts with the external shell and at the maximum pitch angle the inner edge contacts with the inner shell. On the other hand, at the minimum pitch angle the inner edge is at the greatest distance from the corresponding shell and at the maximum pitch angle the outer edge is at its greatest distance from the corresponding shell. As the swing about the leading edges does not exceed approximately 30 degrees, however, these edges in any case will be moved only a relatively short distance from the shells so that the leakage between the edge of the blade and the corresponding shell will be a

relatively small per cent. and the blade will actually act on the air up to substantially its theoretical capacity. The mechanism for operating and controlling the blades is located behind the blades and in such a manner that it does not interfere with the flow of air through the propeller. Furthermore, by inclosing the blades between the two annular shells a maximum volume of air is directed against the blade surfaces which are utilized to the utmost capacity. In the usual construction that portion of the blade extending from the hub of the propeller to approximately the position of the inner shell is utilized to a relatively small extent.

The propeller comprises generally an inner shell 20 and an outer shell 21 both of tubular form between which are interposed a series of blades 23. The leading edges 20 of these blades extend radially of the propeller and are fulcrumed upon shafts 24 secured at their opposite ends in the inner and outer shells, respectively, as shown in Figs. 1 and 2 of the drawings. The inner shell 25 is supported at its forward edges by a spider consisting of a series of tubular spokes 26 extending from a hub 27 which is provided with an elongated barrel 28. The rear edges of both the inner and outer shells 30 are supported by a spider consisting of a series of tubular spokes 30 extending radially from a hub 31 which is formed upon the rear end of the barrel 28. In order to reduce the resistance offered by the spokes to a minimum each set of spokes has substantially the form in cross section indicated at 32 in which the leading portion of each spoke tapers to an edge and is set at the mean pitch angle. In order to additionally 40 brace the propeller structure and insure that it shall be sufficiently rigid under all conditions of strain a series of diagonal struts 33 and 34, respectively, may be provided. The struts 33 extend diagonally from the hub 31 to the front edge of the shell 20 and the diagonal struts 34 extend from the hub 27 to the rear edge of the shell 20. These struts, as indicated in Fig. 2, have substantially the same form in cross section as the 45 spokes of the spider. It will be obvious that this construction presents a compact and rigid form of propeller which affords a minimum resistance to the passage of air therethrough and which utilizes the blade 50 area most effectively. If so desired the outer shell may be further reinforced by a pair of tubular hoops or bands 35 and 36 which extend about the shell at the front and rear edges and have approximately the shape indicated in Fig. 2. In addition braces 21 may extend axially of the outer shell between the ends of the spokes 30 and the pivotal connections of the blades to brace the propeller fore and aft, as shown clearly in Fig. 2.

As stated previously it is highly desirable that the pitch of the blades may be varied within suitable limits to obtain the greatest efficiency from the propeller at varying speeds. To this end mechanism is provided for adjusting the angularity of all of the blades in unison, and for locking the blades in adjusted position. This mechanism in addition is so designed that the variation in pitch may be secured during the continued 70 rotation of the propeller. The sleeve bearing 28 is mounted upon a rotating propeller shaft 40 and a shifting frame 42 having oppositely disposed arms 43 is splined to the shaft at the rear of the propeller. This 75 shifting shaft is connected to the rear or discharge edges of the blades in such a manner that an axial movement of the frame swings the blades angularly the desired amounts. To this end each one of the four 80 arms of the frame is connected at its outer end to the rear portion of a blade through a bell crank lever 44 and connecting link 45. The bell crank, as shown clearly in Figs. 1 and 3, is fulcrumed upon a strut 46 extending from one of the spokes 30 and is so designed that a longitudinal or axial movement of the shifting frame swings the connected blade the desired amount. The movements of the shifting frame are secured 85 through an operating lever 50 fulcrumed upon a stationary stud at 51 and having its lower end connected to a shifting lever 52 through a connecting rod 54. The lever 52 is fulcrumed at 55 upon a lug 56 projecting from a stationary portion of the frame and is provided with a forked upper end 57 the two arms of which are slotted to receive trunnions 59 projecting from the outer 90 stationary housing 60 of an annular ball bearing. The inner race 61 of the bearing is connected to the shifting frame 42 through a sleeve 63. As the inner and outer ball races 61 and 60^b can not have relative longitudinal movement an oscillatory movement of the shifting lever 52 imparts a corresponding movement to the frame 42 and through the interposition of the ball bearing this shifting movement is readily accomplished and without 95 imposing any substantial strain upon the operating parts. In order to lock the shifting frame and the propeller blades in adjusted position the operating lever 50 is provided with the usual detent 64 which engages with a toothed rack 65, as shown clearly in Fig. 2. This detent is released to move the operating lever through the usual handle 66. It is important that the shifting frame be made to assume a slightly different 100 angular position for each different longitudinal position and to this end the sleeve 63 is provided with curved slots 68 which receive the opposite ends of a pin 70 extending through the propeller shaft 40. With 105

this construction when the shifting frame is made to assume different longitudinal positions it is also moved angularly with relation to the propeller housing a sufficient amount 5 to compensate for the angular movement of the connected arm of the bell crank lever 44. The provision of three or more blades in the propeller has the advantage that it secures a large axial thrust at relatively low 10 speeds and owing to the character of the present construction with the blades interposed between two tubular shells greater efficiency arises due to low friction and eddy losses, the propeller having only a small retarding resistance from the parts between 15 the hub and inner shell. Furthermore it will be observed that an extremely compact and efficient construction has been provided for varying the pitch of the blades as desired, without interfering with the flow of air through the blades or otherwise detracting from the efficiency.

In order to direct the maximum volume of air against the propeller blades the inner 20 and outer shells are provided at their forward edges, respectively, with curved directing lips 110 and 111 which, as shown clearly in Fig. 2, are adapted to collect and direct the air against the blades during the 25 advancing movement of the propeller. This construction assists the stream line flow into the space between the shells and insures an abundance of air for the blades to act upon.

A modified construction for changing the 30 pitch of the blades is indicated in Figs. 7 to 11, inclusive. In this construction an oscillatory shaft 90 extends parallel to each of the spokes 30 and in close proximity thereto and is provided with an operating 35 arm 91 secured to its outer end which is connected with the rear or discharge edge of the corresponding blade by a link 92. Each of these shafts is guided at its inner and outer ends in bearing plates 93 and 94 secured 40 to the adjacent spoke 30. By partially rotating all of these shafts in unison the required efficiency of the blades may be secured. To this end a shifting frame, indicated at 95, is provided. This frame has a 45 plurality of arms corresponding in number to the number of shafts 90 (in the present case four) extending longitudinally of the propeller shaft 40. Each of these arms has formed thereon a series of rack teeth 97 50 which mesh, respectively, with coöperating

pinions 98 secured to the inner ends of the shafts 90. Thus it will be seen that an axial movement of the shifting frame 95 through the coöperating racks and pinions rotates the shafts 90 in unison and varies the angularity of the connected blades. The shifting frame is connected directly to the inner race 100 of a ball bearing having an outer race 101. A longitudinal movement is imparted to the outer ball race through the 55 same construction described previously and consisting of the operating lever 50, the connecting rod 54 and the shifting lever 52 having the forked upper end 57 receiving a pair of trunnions 59 which project outwardly 60 from the housing 60 of the ball race 101.

A further modification of the propeller construction is indicated in Figs. 6 and 11 in which the diagonal braces comprise a plurality of short struts 102 which extend, respectively, from opposite ends of the bearing 28 and the front and rear edges of the inner shell to a centrally disposed hub 105, as shown in Fig. 6.

While it is preferred to employ the specific 80 construction and arrangement of parts shown and described, it will be understood that this construction and arrangement is not essential except so far as specified in the claims, and may be changed or modified 85 without departing from the broader features of the invention.

The invention having been described, what is claimed is:

1. A propeller comprising inner and outer 90 tubular shells, a series of blades interposed between the shells, a spider having a series of tubular spokes supporting the front edge of the inner shell, a second and similar spider supporting the rear edges of the inner 95 and outer shells, and means for simultaneously varying the angularity of all the blades.

2. A propeller comprising a supporting frame, a series of blades mounted upon the 100 frame, an operating shaft connected to each blade, a shifting frame having a series of arms corresponding in number to the operating shafts, a rack formed upon each arm, a pinion secured to the end of each shaft and 105 meshing with the rack, and means for moving the frame longitudinally to rotate the shaft and vary the angularity of the blades.

GUY B. COLLIER.
